UNITED STATES PATENT OFFICE.

JOHN FRANCIS BILLS, OF CASPER, WYOMING.

FLOOR-SURFACING MACHINE.

1,112,253.

Specification of Letters Patent. Patented Sept. 29, 1914.

Application filed October 29, 1913. Serial No. 798,066.

To all whom it may concern:

Be it known that I, JOHN F. BILLS, a citizen of the United States, residing at Casper, in the county of Natrona and State of Wyoming, have invented new and useful Improvements in Floor-Surfacing Machines, of which the following is a specification.

This invention relates to floor surfacing machines, the broad object of the invention being to produce a motor driven machine of the class referred to in the form of a wheeled truck, which is propelled along the floor by means of the motor and adapted to be steered by the operator, the machine embodying means for abrading and polishing the floor and bringing the same to the necessary degree of smoothness.

A further object of the invention is to provide means for raising and lowering the main body of the truck so as to obtain the desired pressure of the surfacing rolls against the floor to obtain the best results and to provide means for conducting off the dust to a suitable receptacle.

25 A further object of the invention is to provide means whereby the machine may be reversed or made to travel either forwardly or backwardly as occasion may require.

A further object of the invention is to 30 provide a machine the construction of which will admit of the same being driven close to the wall or washboard thereby enabling the entire surface of the floor to be finished.

A further object of the invention is to 35 provide a surfacing roll the construction of which will admit of the ready application thereto and removal therefrom of sheets of sand paper or other abrading and polishing material while obtaining a thorough stretching of said sheets around the roll.

With the above and other objects in view, the invention consists in the construction, combination and arrangement of parts, as will hereinafter be more fully described, 45 illustrated and claimed.

In the accompanying drawings:—Figure 1 is a plan view of the floor surfacing machine embodying the present invention. Fig. 2 is a bottom plan view of the same. 50 Fig. 3 is a side elevation of the machine showing the mechanism for rotating the surfacing rolls. Fig. 4 is a vertical longitudinal section through the machine. Fig. 5 is a vertical cross section through the machine on the line 5—5 of Fig. 2. Fig. 6 is a

vertical cross section through the machine on the line 6—6 of Fig. 2. Fig. 7 is a detail vertical longitudinal section showing part of the raising and lowering means. Fig. 8 is an elevation of one of the surfacing rolls, 64 partly broken away in section. Fig. 9 is a cross section on the line 9—9 of Fig. 8 showing the clamping jaws open. Fig. 10 is a similar view showing the clamping jaws closed and the surfacing sheet clamped in 65 place around the roll. Fig. 11 is a detail perspective view of one end of the cam shaft of the surfacing roll.

The floor surfacing machine contemplated in this invention comprises a horizontal 70 platform 1 which constitutes a portion of the frame of the truck which is supported by traction wheels 2 and steering wheels 3 hereinafter more particularly referred to. All of the mechanism hereinafter described 75 as contained below the platform 1 is housed in by the sides 4 and front and rear ends 5 and 6 respectively which serve to conceal the said mechanism and prevent the dust from flying about in the room. 80

The machine is driven along the floor, and the surfacing rolls and other parts of the mechanism are actuated by a motor 7 which is mounted about centrally of and upon the platform 1, an electric motor being shown 85 and 8 designating the conductor wires by means of which the necessary current is transmitted to the motor.

9 designates the motor shaft which has fast thereon a bevel gear wheel 10 which 90 meshes with and drives a bevel gear wheel 11 fast on the upper end of a vertical transmission shaft 12. This shaft is journaled in a bearing 13 secured to the platform as shown in Fig. 4 and has fast on its lower end 95 another bevel gear wheel 14. The wheel 14 meshes with and drives another bevel gear wheel 15 fast on a worm shaft 16 extending horizontally and transversely of the truck frame and having fast thereon a worm 17 100 which meshes with and drives a worm gear 18 fast on the main drive shaft 19.

The drive shaft 19 is mounted in bearings 20 and 21 under the platform 1 and has fast on its rear end a bevel gear wheel 22 which 105 meshes with and drives a pair of opposed bevel gear wheels 23 and 24 one or the other of which is always loose on the driving axle 25, said axle having the traction wheels 2 above referred to fast thereon. 110

Mounted slidably on the driving axle 25 is a clutch 26 having opposite clutch faces as shown in Fig. 2 movable alternately into and out of engagement with clutch faces 27 and 28 on the inner faces of the wheels 23 and 24, thus enabling either one of said wheels to be locked to the driving axle 25 according to the direction in which it is desired to propel the machine.

10 The clutch 26 is provided with a groove 29 to receive a clutch shifting fork 30 having the arms 31 thereof extended sufficiently to admit of a certain degree of up and down movement of the driving axle 25 as indicated in Fig. 4 for the purpose of permitting the machine and the weight thereof to rest more or less on the surfacing rolls hereinafter described. The fork 30 extends upwardly above the driving axle 25 and is pivotally mounted at its upper end beneath the platform as shown at 32. The fork 30 is operated by means of a hand operated clutch lever 33 as shown in Fig. 3, said lever being provided with a thumb latch 34 which engages a stationary segmental rack 35 extending upward from the platform 1. Connected to the clutch lever 33 is a connecting rod 36 which extends rearwardly and connects to one arm of a bell crank lever 37 movable on a vertical axis. From the other arm of said bell crank lever 37 a connecting rod 38 extends to the clutch shifting fork 30 so that by moving the hand lever 33, the clutch 26 may be shifted lengthwise of the driving axle 25 so as to engage one or the other of the wheels 23 or 24 and lock the same to the driving axle. In this way the operator standing on the platform 1 may quickly reverse the driving mechanism and cause the machine to travel forward or backward as may be necessary.

The steering wheels 3 are mounted in forks 39 having upwardly extending stems 40 which are journaled in a bolster 41 as indicated in Fig. 4, the crowns 42 of the forks bearing against the under side of the bolster 41. At their upper ends the fork stems 40 are provided with crank arms 43 coupled together by a yoke bar 44 causing both crank arms 43 to turn together. The yoke bar 44 is operated by means of a steering lever 45 within reach of the operator, said lever being fast on the upper end of a steering post 46 journaled in a suitable supporting frame. 55 47 extending upwardly from the platform 1. On the lower end of the post 46 is a crank arm 48 which is pivotally connected at 49 to the yoke bar 44. It will now be seen that when the operator moves the steering lever 45 to one side or the other, the steering wheels 3 are correspondingly turned and in this way the direction of movement of the machine as a whole may be governed.

The driving axle 25 is journaled at its 65 opposite ends in bearings 50 carried by a

pair of vertically adjustable bearing slides 51 of dove-tailed shape in cross section and movable in vertically extending guides 52 having guide ways 53 of dove-tailed shape corresponding with the shape of the bearing slides 51 as shown in Fig. 6. In like manner the opposite extremities of the bolster 41 are carried by vertically movable bearing slides 54 movable in guide ways 55 on the sides of the truck, the slides and guides 54 and 55 corresponding in shape with those 51 and 52 above described and as seen in Fig. 2.

In order to provide for the vertical adjustment of the bearing slides 51 and 54, each of said slides is provided with a rack face 56, and these rack faces are engaged by two sets of sectors 57 and 58 shown as arranged respectively at the rear and front of the machine. By reference to Fig. 7 it will be seen that the front and rear sectors are provided with arms 59 and 60 which extend beyond the fulcrum points 61 of the sectors and have attached thereto longitudinally extensible links 62 which are pivotally connected at 63 to the sector arms and pivotally connected at their opposite ends as shown at 64 to a crank arm 65 on a raising and lowering shaft 66 journaled in suitable bearings in the frame of the truck and having fast thereon a raising and lowering hand lever 67 provided with a thumb latch 68 engaging a stationary segmental rack 69 secured to and extending upward from the platform 1 as shown in Fig. 3. It will now be understood that by moving the hand lever 67 and thereby turning the shaft 66, the sectors 57 and 58 will be turned to raise or lower the traction wheels 2 and the steering wheels 3 for the purpose of taking some of the weight 103 from the surfacing rolls hereinafter described or placing increased weight thereon as may be found necessary.

As shown in Figs. 4 and 5 the links 62 are extensible relatively to the lower pivots 63. By removing said pivots 63, the lower ends of the links may be disconnected from the levers 59 and 60, after which the jam nuts shown in said Figs. 4 and 5 may be loosened and the clips at the lower extremities of the links 62 may be turned on their threaded connection so as to increase or diminish the length of the links, after which the pivots 63 may be reinserted. Thus either one of the links 62 may be increased or diminished in 115 length for the purpose stated.

At both the front and rear ends of the machine I locate the floor surfacing rolls, 70 designating the front roll and 71 the rear roll. One of said rolls is illustrated in detail in Figs. 8 to 11 inclusive wherein it will be observed that each roll comprises oppositely located disk-shaped heads 72 connected by a central shaft 73 which is journaled in bearings 74 on the sides 4 of the 125

housing, the disk-shaped heads 72 being recessed as shown at 75 to receive the bearings 74. A sheet metal cover 76 fits at its opposite ends around the disk-shaped heads 72 and forms the cylindrical wall of the roll. One of the longitudinal edges of the cover 76 is fixedly secured to a stationary clamping jaw 77 which is set into recesses 78 in the heads 72 as shown in Figs. 9 and 10. Movable in the same recesses 78 is a movable clamping jaw 79 shiftable toward and away from the fixed clamping jaw 77 by means of a plurality of jaw carrying stems 80 which are connected to a corresponding number of clamping levers 81 pivotally mounted at 82 within the body of the roll. Each of the levers 81 is provided with a cam receiving slot 83 in which operates a cam projection 84 on a cam shaft 85 journaled in bearings 86 in the heads 72 and projecting at one end beyond one of the heads, the projecting extremity of the cam shaft being squared as at 87 to receive a suitable wrench for the purpose of turning the cam shaft. 88 designates an abrading or polishing sheet which is wrapped around the roll. By referring to Figs. 9 and 10 it will now be understood that a sheet of sand paper or a sheet of fabric such as carpet may be applied around the cover 76 of the roll and the edges thereof inserted between the clamping jaws 77 and 79. This is done while the jaws are open or spread apart as shown in Fig. 9 and when the movable jaw is closed on the fixed jaw, the cover 76 which is attached at its free edge to the movable jaw 79, and the abrading or polishing sheet, are placed under tension, the abrading or polishing sheet being thus effectively stretched around the surfacing roll and securely clamped in place thereon. This provides an easy and practical way of clamping sheets of abrading or polishing material on the surfacing rolls and removing the same quickly therefrom. It will also be observed that the jaws 77 and 79 extend at an angle to the major axis of the roll so as to distribute the wear and tear on the meeting edges of the surfacing sheet 88. The surfacing rolls are driven by the following means. The shafts of the front and rear rolls are provided outside of one of the truck sides 4 with front and rear bevel gear wheels 90 and 91, respectively, engaged by other bevel gear wheels 92 and 93 on the opposite ends of a pair of inclined roll driving shafts 94 and 95. At their adjacent ends these shafts are provided with bevel gear wheels 96 and 97 which mesh with a common driving bevel gear 98 fast on the worm shaft 16. By reference to Fig. 2 it will be observed that the side of the machine opposite with the side on which the gearing just described is mounted is left perfectly plain and unobstructed so that it may operate in

close proximity to the washboard in a room, thus adding to the practical value of the machine.

Referring now to Fig. 4 it will be observed that a dust hood 99 embraces each of the surfacing rolls 70 and 71 and is fixedly secured to the truck frame. Each of said hoods is offset to form a suction gutter 100 and from these gutters, suction pipes 101 and 102 lead upwardly through the platform 1 and connect with the casing 103 of a suction fan, the said casing having its discharge spout 104 extending horizontally to enable a dust bag to be applied thereto to receive the material as it is sucked from the hoods 99. The fan shaft 105 is shown as driven by a bevel pinion 106 which meshes with the bevel gear wheel 11 hereinabove described on the vertical transmission shaft 12. 107 designates a tool box provided with a hinged cover 108 at the front of the machine. 109 represents a supporting bar for the electric conductors 8, said supporting bar 109 being detachably mounted in socket pieces 110 fastened to the steering post supporting frame 47.

From the foregoing description it will now be seen that the floor surfacing machine is propelled by means of a motor carried thereby and driving the traction wheels thereof. The truck may be moved either forwardly or backwardly, the direction of movement thereof being readily controlled by the reversing mechanism described. The main body of the truck may be raised and lowered with respect to the traction and steering wheels so as to bring any desired load to bear on the positively driven floor surfacing rolls. The steering of the machine is controlled by the operator standing on the platform who also has the raising and lowering lever and the clutch lever at hand. As often as may be necessary, the surfacing rolls may be raised out of contact with the floor and new sheets of abrading or polishing material may be placed on the rolls in lieu of the worn out sheets, this being accomplished easily and quickly by the clamping means hereinabove described. The dust is gathered up by the suction pipes and conveyed and discharged into a suitable receptacle preferably in the form of a bag or sack attached to the nozzle of the suction fan.

What I claim is:—

1. In a floor surfacing machine, the combination of a truck frame, a platform thereon, a motor mounted on said truck, traction wheels supporting said truck and driven by said motor, steering wheels also supporting said truck, manually controlled steering mechanism, and means operable from above said platform for raising and lowering the truck relatively to the truck supporting wheels, said means comprising pairs of op-

120

125

130

positely arranged vertically movable slides having rack faces, sector gears meshing with said rack faces, a hand lever, and connections between said sector gears and hand lever.

2. In a floor surfacing machine, the combination of a truck frame, a platform thereon, a motor mounted on said truck, traction wheels supporting said truck and driven by 10 said motor, steering wheels also supporting said truck, manually controlled steering mechanism, and means operable from above said platform for raising and lowering the

truck relatively to the truck supporting wheels, said means comprising pairs of oppositely arranged vertically movable slides having rack faces, sector gears meshing with said rack faces, a hand lever, and longitudinally extensible connections between said sector gears and hand lever. 15

In testimony whereof I affix my signature in presence of two witnesses.

JOHN FRANCIS BILLS.
